CORN POPPER

William E. Gundelfinger, St. Louis, Mo., assignor
to Knapp-Monarch Company, St. Louis, Mo., a
corporation of Missouri

Application July 15, 1940, Serial No. 345,573

3 Claims. (Cl. 259—109)

My present invention relates to corn poppers and more particularly to agitators therefor, the particular agitator disclosed being of such design and character that it readily conforms to the bottom of the popper during the agitating operation.

One object of the invention is to provide an agitator which can be made at a relatively small cost, yet which will produce the desired results and make possible the provision of an efficient agitator in a low priced popper.

With these and other objects in view, my invention consists in the construction, arrangement and combination of the various parts of my device whereby the objects contemplated are attained, as hereinafter more fully set forth, pointed out in my claims and illustrated in the accompanying drawing. Although the invention is susceptible of a variety of embodiments, it is unnecessary to fully describe and illustrate more than one in order to give a full understanding of the invention both from its structural and functional standpoints. Accordingly, I have illustrated a preferred and desirable embodiment of the invention in the accompanying drawing, in which:

Figure 1 is a plan view of a corn popper structure embodying my invention, the cover thereof being removed;

Figure 2 is a partial sectional view on the line 2—2 of Figure 1, and

Figure 3 is a sectional view on the line 3—3 of Figure 1.

On the accompanying drawing, I have used the reference character K to indicate generally a popper kettle. The kettle K has a lid L and both may be inexpensively formed of sheet metal. The popper illustrated is of the electric type, a casing 10 being provided for the heating element (not shown). The terminals for the heating element are illustrated at 12.

The kettle K may be supported in any suitable manner as by brackets 13, legs 14 and screws 15. The lid L is provided with the usual knob 16 for handling it and with steam-escape openings 17.

My agitator consists of a crankshaft 18 journaled in opposite portions of the wall of the kettle K. To prevent longitudinal movement, a pair of ears 19 are pinched into opposite sides of the crankshaft and enclosed in a sheet metal boss 20. One end of the crankshaft 18 terminates in a crank 21 for operating the agitator.

My agitator further includes a spring wire element 22 having its terminal ends, indicated at

23 and 24, wrapped around the crankshaft 18 adjacent washers 25 on the crankshaft 18. The washers 25 in turn are located adjacent the wall of the kettle.

It will be observed that the distance along the wall of the kettle from one journal of the crankshaft to the other is a semicircular arc having the crankshaft on its diameter. According to my invention, the shape of the kettle below the crankshaft is of shallower than semicircular vertical section. Hence the distance along the kettle section as viewed in Figure 2 is less than as viewed in Figure 1.

The coil 23 is wrapped so that it is tighter than the coil 24. The purpose of this construction is so that the coil 23 firmly grips the crankshaft 18, while the coil 24 grips it less firmly. Accordingly, in operation the wire 22 (which is normally formed semi-circular, as shown by full lines in Figure 1) first conforms to the cylindrical wall of the kettle when the crank 21 is in the position indicated at a. As the crank is rotated, the wire 22 will be dragged across the relatively shallow bottom of the kettle K, and will be placed under endwise compression, causing it to assume successively positions 22a, 22b, 22c and 22d, as the crank arm 21 is successively turned to positions a, b, c and d.

In passing through the various positions illustrated, the wire 22 will drag forcefully across the bottom of the kettle K, thereby effectively preventing sticking and burning of the popcorn, and will effect an efficient agitation of the corn during the popping process. The wire 22 is sufficiently light and is resilient enough to effect such scraping throughout the entire surface of the bottom of the kettle from the time the wire enters at position 22 until it leaves at position 22d in Figure 1. Due to the coil 23 gripping the crankshaft 18 more firmly than the coil 24, the left end of the wire at position 22b in Figure 1 will drag behind the right end, thus producing a letter S or double bowed formation in the wire which permits it to follow the contour of the bottom of the kettle and accommodate itself to the decreased distance across the bottom from one journal of the crankshaft 18 to the other at the lower central position 22b of the agitator. The resiliency of the wire 22 also tends to keep the coils 23 and 24 closely adjacent the washers 25 and the coils make an inexpensive and effective operative connection between the crankshaft and the agitator. At the same time, the coils serve as a clutch connection which prevents operation of the agitator in a reverse direction.

As many changes could be made in the foregoing construction and many apparently widely different embodiments of this invention could be made without departing from the scope thereof, it is intended that all matter contained in the above description or shown in the accompanying drawing shall be interpreted as illustrative and not in a limiting sense. It is also to be understood that the language used in the following claims is intended to cover all of the generic and specific features of the invention herein described and all statements of the scope of the invention which, as a matter of language, might be considered as falling therebetween.

I claim as my invention:

1. In a corn popper construction, a popper kettle circular in horizontal section, having a substantially cylindrical vertical wall, a horizontally arranged crank shaft journalled through opposite portions of said cylindrical wall on a diameter of said kettle, the portion of said kettle below said crankshaft constituting a dished bottom of shallower than semicircular vertical section, and an agitator element on said shaft comprising a normally U-shaped spring wire having the terminal ends of its arms mounted on said crank shaft only by wrapping therearound, whereby the shaft may be freely rotated in one direction, and said wrappings will frictionally grip the crankshaft when it is rotated in the other direction, said wrappings being located on said crank shaft adjacent said wall of said kettle and one of them being wrapped tighter than the other, the length of said wire between said wrap-

pings being substantially half the internal circumference of said kettle on a horizontal plane through said crank shaft.

5 2. A corn popper including a kettle circular in horizontal section, a horizontally arranged crank shaft journalled on a diameter of said kettle, the portion of said kettle below said crank shaft constituting a dished bottom of shallower than semi-circular vertical section, and an agitator element 10 comprising a bowed length of spring wire having its ends mounted on said crank shaft adjacent the walls of the kettle, the length of said wire between said mountings being approximately half the internal circumference of said kettle on a horizontal plane through said crank shaft.

15 3. A corn popper including a kettle circular in horizontal section, a horizontal crank shaft journalled on a diameter of said kettle, the portion of said kettle below said crank shaft constituting 20 an upwardly concave bottom of shallower than semi-circular vertical section, and an agitator element on said shaft comprising a bowed length of spring wire having its terminal ends mounted on said crank shaft only by wrapping therearound, whereby the shaft may be freely rotated in one direction, and said wrappings will frictionally grip the crankshaft when it is rotated in the other direction, said wrappings being located 25 on said crank shaft adjacent the walls of the kettle, the length of said wire between said mountings being slightly greater than half the internal circumference of said kettle on a horizontal plane through said crank shaft.

WILLIAM E. GUNDELFINGER.
